UNITED STATES PATENT OFFICE.

JOHN RIEPPEL, OF COWANESQUE, PENNSYLVANIA.

FRictional CLUTCH.

No. 806,000

Specification of Letters Patent.

Patented Nov. 28, 1905.

Application filed August 11, 1904. Serial No. 220,893.

To all whom it may concern:

Be it known that I, JOHN RIEPPEL, of Cowanesque, in the county of Tioga and State of Pennsylvania, have invented certain new and useful 5 Improvements in Frictional Clutches; and I do hereby declare the following to be a full, clear, and exact description of the invention, such as will enable others skilled in the art to which it appertains to make and use the same.

10 The object of this invention is to provide improvements in that class of friction-clutches whose parts are so constructed and arranged that the binding of the friction-shoes is effected by the swinging of the latter outwardly 15 from a common point by means which will firmly hold them in their adjusted positions and which will allow them to readily return to their normal positions upon the release of pressure.

20 A further object is to provide improved means for readily compensating for wear without the necessity of dismantling the parts.

The invention will be hereinafter fully set forth, and particularly pointed out in the 25 claims.

In the accompanying drawings, Figure 1 is an end elevation. Figs. 2 and 3 are cross-sectional views on lines 2 2 and 3 3, Fig. 1. Fig. 4 is a sectional view on line 4 4, Fig. 1. Fig. 30 5 is a view of portions of one of the shoe-actuating arms and one of the shoes. Fig. 6 shows a modified form; and Fig. 7, a cross-section on line 7 7, Fig. 6.

Referring to the drawings, 1 designates the 35 shaft, and 2 a band wheel or pulley which is shown as having a ring or flange 3 secured to its spokes, but of considerably less diameter than the pulley. Upon the shaft is fitted a sleeve 4, whereon the pulley is held loosely by 40 a fixed collar 5. Upon this sleeve is secured a cross-piece 6, forming two lateral arms, upon each of the ends of which are pivoted the ends of a pair of clutch-shoes 7. I have shown two pairs of clutch-shoes, the free ends of the shoes 45 of adjacent pairs being formed with angularly-extended flanges 8, having coincident openings through which is passed a pivot-rod 9. One of the flanges 8 of one clutch-shoe is smooth on its outer surface, and within the opening 50 of such flange is fitted an exteriorly-threaded sleeve 10, having an outer flanged end 12, wherein are formed recesses 13 to permit of the insertion of a tool for readily adjusting the sleeve so as to compensate for wear. This 55 flange is transversely split to form clamping-jaws 8^a for the sleeve 10, a bolt 8^b holding the

sleeve in its adjusted position. (See Fig. 3.) The flange of the other shoe is formed with an irregular or cam-like surface 14, designed to conform to a correspondingly-formed surface 60 on the inner end of an adjusting-arm 15, pivoted on rod 9 between the contiguous ends of the adjacent pairs of shoes. These arms at their pivot ends on the sides opposite to those formed with the cam or irregular surfaces are flat, so as 65 to fit flush against the flanged ends of sleeves 10. The pivoted ends of the shoes are formed with openings to accommodate nutted rods or bolts 16, extending outwardly from the two lateral arms. At their outer ends the shoe- 70 actuating arms 15 are pivotally connected by links 17 to a collar 18, movable longitudinally of shaft 1, such collar carrying in its peripheral groove a split ring 19, to which a shifting-lever (not shown) may be connected. To 75 maintain this adjusting-collar in proper position and guard against any lateral strain on the adjusting-arms, I form such collar with an apertured flange 20 to accommodate a guide bolt or rod 21, extending outwardly from the 80 cross-piece 6.

22 designates springs mounted on each of the pivot-rods 9, which springs are compressed when the arms are turned to force the shoes outwardly into engagement with the ring or 85 flange and the tendency of which is to immediately withdraw the shoes from frictional engagement with the ring or flange once the pressure of the cam ends of the adjusting-arms is released.

In practice the shoes are normally out of frictional engagement with the ring or flange of the clutch-pulley. When it is desired to actuate the clutch, the collar 18 is moved outwardly, so as to turn the adjusting-arms on 95 their pivots. These arms by reason of the cam-surfaces on their inner ends force the adjacent ends of the two pairs of shoes outwardly, such shoes swinging or turning on their pivots, so that the contact is had with 100 the ring or flange under the radial movements of the shoes. In this way the clutching is readily and easily effected and all danger of slipping is avoided. As soon as the collar 18 is moved inwardly the springs 22 at once 105 cause the free ends of the two pairs of shoes to move toward each other, and thus release the bite or hold on the ring or flange. As the cam-surfaces wear, and likewise to compensate for the wear of the engaging surfaces 110 of the shoes, the sleeves 10 are readily turned so as to always secure a snug fit between the

flanges 8 of the shoes and the pivot ends of the adjusting-arms.

Although I have specified a ring or flange secured to the spokes of a pulley, it is obvious that the shoes may engage directly with the pulley-rim, the latter serving the same purpose as the friction-ring 3. It is also manifest that any number of pairs of clutch-shoes may be employed. In some instances I have used three pairs and in others four pairs. Then, again, in small pulleys I have used but a single pair, as shown in Figs. 6 and 7, in which instance but one lateral arm is necessary, the cross-piece being then extended in but one direction. In this arrangement I have shown the apertured flanges for the pivot-rods 9 as extended outwardly instead of inwardly, as in the other instances. Other changes and modifications may be made and still be within the scope of my invention.

The advantages of my invention are apparent and will be readily appreciated by those skilled in the art.

I claim as my invention—

1. The combination with the shoes pivoted each at one end and free at the other, said shoes having at their free ends angularly-extended flanges, one flange of adjacent shoes having a cam-surface, the other flange having clamping-jaws, a sleeve adjustably held by said jaws, a pivot-rod passed through said former flange and said sleeve, an adjusting-arm mounted on said pivot-rod having on one side a cam-surface to engage the corresponding surface of one of the flanges, its other side engaging the face of said adjustable sleeve, and means for actuating said arm.

2. The combination with the shoes pivoted each at one end and free at the other, said shoes having at their free ends angularly-extended flanges, rods passed through said

flanges, adjusting-arms mounted on said rods intermediate said flanges, means for actuating the arms, means for forcing said shoes outwardly as the arms are moved in one direction, and springs encircling said rods for returning said shoes to their normal positions when relieved of the pressure of said arms.

3. The combination with the sleeve and the lateral arms, of the shoes arranged in pairs, the shoes of each pair being pivoted at adjacent ends to said arms, said shoes at their outer ends having angularly-extended flanges, the flange of one shoe having a cam-like surface, an adjustable flanged sleeve fitted in the flange of the other shoe, rods passed through adjacent flanges, springs on said rods, adjusting-arms mounted on said rods having each on one side a cam-like surface for coacting with the corresponding surface of the adjacent flange, an endwise-movable sleeve, and links connecting the latter to the outer ends of said arms.

4. The combination with the cross-piece forming lateral arms, of the clutch-shoes arranged in pairs, the shoes of each pair being pivoted to said cross-piece, adjusting-arms fitted between the free ends of adjacent shoes for forcing the latter outwardly, a longitudinally-movable sleeve to which said adjusting-arms are connected, and a guide extended outwardly from said cross-piece, said collar having an apertured flange to accommodate said guide.

In testimony whereof I have signed this specification in the presence of two subscribing witnesses.

JOHN RIEPPEL.
